HUGH H. PADGETT AND LOUIS L. BOOKOUT, OF LINDALE, TEXAS.

KNOCKDOWN FRAME.

1,103,823.

Specification of Letters Patent. Patented July 14, 1914.

Application filed April 21, 1913. Serial No. 762,537.

To all whom it may concern:

Be it known that we, HUGH H. PADGETT and LOUIS L. BOOKOUT, citizens of the United States, residing at Lindale in the 5 county of Smith and State of Texas, have invented certain new and useful Improvements in a Knockdown Frame, of which the following is a specification.

Our invention relates to a knockdown 10 frame, and particularly relates to a knockdown frame for supporting a block and tackle.

The object of our invention is to provide a frame which may be quickly set up and 15 taken down, and which will support a block and tackle for the purpose of raising a certain receptacle after the same has been loaded with sand or gravel, the same being of such a size and form that a wagon may be 20 driven beneath the same after said receptacle has been hoisted, and the contents of the receptacle may be discharged into the wagon.

Another object of the invention is to provide 25 a device for locking the fall rope of the block and tackle after the load has been raised.

Finally the object of our invention is to provide 30 a device of the character described that will be strong, durable, simple and efficient and comparatively easy to construct.

With these and various other objects in view, our invention has relation to certain 35 novel features of the construction and operation, an example of which is described in the following specification, and illustrated in the accompanying drawing, wherein:

Figure 1 is a view in side elevation of our 40 knock-down frame. Fig. 2 is a view of the same in front elevation, certain parts being broken away. Fig. 3 is a detail sectional view, the section being taken upon the line $x-x$ of Fig. 2. Fig. 4 is a detail sectional view showing the device for locking the fall 45 rope after the load has been raised by the block and tackle. Fig. 5 is another view of the same mechanism.

In the drawings like reference characters 50 are employed to designate similar parts in the several views.

Our frame primarily comprises three members, two of which are of triangular 55 shape and are vertically mounted, and the third of which is mounted transversely between the upper extremities of the side members. Each of the side members is

formed by two oppositely inclined beams 1 bolted together at their upper ends and rigidly connected at their lower ends by a horizontal member 2. The transverse member, 60 which is separable from the two upright side members, comprises a pair of spaced parallel beams 3 bolted to the lower end of two beams 4 inclining toward each other at an acute angle with the members 3 and 65 rigidly connected at their upper extremities. The opposing faces of the members 3 are correspondingly slotted adjacent to the extremities of said members as indicated at 5, the slots 5 being so shaped as to fit snugly 70 over the upper ends of the two side frames. Thus when the transverse member is mounted in the proper relation to the side members of our frame, the inclined faces of the members 1 form seats for the slotted ends 75 of the transverse member.

A further support for the extremities of the transverse member is furnished by the two horizontal timbers 6 respectively bolted to the inner faces of the side members of 80 our frame, a short distance below the upper ends of said side members.

A staple 7 is mounted at the juncture of the members 4 beneath the said members which staple forms a support for the upper 85 block 8 of a block and tackle. The fall rope of the block and tackle is designated by the numeral 9 and the fall pulley by the numeral 10.

In one of the side members of the frame, 90 there is embodied a vertical beam 11, disposed in a symmetrical relation to the beams 1, of the side frame with which said beam 11 is correlated. In the lower portion of the beam 11 there is formed a transverse 95 slot 12, upon the floor of which is rigidly secured a bracket 13 having in its top a slight groove 14. Upon the inner face of the vertical member 11 opposite to the slot 12, there is mounted a small bracket 15 in 100 which is supported a small spindle 16 the extremities of which furnish a pivotal support for a lever 17 projecting outwardly from the frame, said lever having a yoke 105 formed on its pivoted end the sides of which yoke are disposed adjacent to the side faces of the member 11. The sides of the yoke 18 serve as bearings for a spindle 19 parallel to the spindle 16 and passing through vertical slots 20 formed in the side walls of the 110 slot 12. Centrally within the slot 12, a pulley 21 is mounted fast upon the spindle

19, the fall rope of the block and tackle being passed through the slot 12 and carried on the pulley 21 beneath the same. When the lever 17 is subjected to an angular downward displacement about the axis formed by the pintle 16, the fall rope will be clamped between the pulley 21 and the bracket 13. In order that the lever may be firmly held in a position to lock the fall 10 rope, a ratchet rack 22 is formed upon the upper edge of said lever and is adapted to be engaged by a dog 23 pivoted upon the outer face of the beam 11 just above the slot 12.

15 In using the above described apparatus, after a receptacle has been filled with sand, dirt or gravel and raised by the block and tackle to the desired elevation, the fall rope may be locked by the mechanism just described so that the receptacle will be held in its elevated position without necessity of maintaining a strain on the end portion of the fall rope. A wagon may then be driven between the side members of the frame and 20 beneath the transverse member thereof and when the wagon is beneath the receptacle, the contents of the latter may be discharged 25 into the wagon bed.

The above described frame may be reduced to a very compact form when being 30 transported from place to place and may be very quickly set up or taken down.

The invention is presented as including all such modifications and changes as properly come within the scope of the following claims:

What we claim is:

1. A knockdown frame comprising two triangular upright side members, and a third member rigidly connecting the upper 40 extremities of the side members, said third member comprising two parallel timbers, secured at each side of two members inclining upwardly toward each other, the last named members being rigidly connected at 45 their upper ends.

2. A knock-down frame, comprising two triangular upright side members, and a third member comprising two parallel timbers secured at each side of two timbers inclining upwardly toward each other, and rigidly connected at their upper ends, the opposite faces of said parallel timbers being grooved at their extremities to receive the pointed upper ends of the side members.

In testimony whereof we have signed our names to this specification in the presence of two subscribing witnesses.

HUGH H. PADGETT.
LOUIS L. BOOKOUT.
